DISTILLATION OF READILY VOLATILIZABLE METALS

Friedrich Johannsen, Magdeburg, Germany, assignor to firm Fried. Krupp Grusonwerk Aktiengesellschaft, Magdeburg-Buckau, Germany

Application February 2, 1933, Serial No. 654,965
In Germany February 12, 1932

4 Claims. (Cl. 75—28)

The present invention relates to the distillation of readily volatilizable metals, such, for example, as zinc or cadmium, in one or more retorts built into a rotary furnace.

5 One object of the invention is to effect the separation of the metal vapours from the solid substances in the retort within the furnace at a temperature at which condensation of the metal vapours upon the various portions of the charge 10 is substantially prevented, in the case of zinc, at 900—1000° C.

Another object of the invention is the provision, in a rotary furnace employed for the distillation of metals, of means for effecting the 15 separation of the metal vapours from the solid substances within the furnace. The metal vapours may then be carried away at that side of the retort at which the residue is removed or in the centre of the retort or at a point lying close 20 to the charging end of the retort, but in any case at a point where the retort charge possesses so high a temperature that condensation of the metal vapours on the relatively cold charge will be avoided.

25 Further objects and advantages of the invention will become apparent from the following description of certain forms of apparatus according to the invention referred to by way of example only and illustrated diagrammatically in the accompanying drawings, wherein:—

Figure 1 is a longitudinal section through an apparatus wherein a retort is arranged on the axis of rotation of the furnace.

Figure 1a is an enlarged fragmentary view of 35 the connection between the retort and condenser of Figure 1.

Figure 1b is a detail view of one of a pair of valves which may be used with the residue discharge coil or helix.

40 Figure 1c is an enlarged vertical sectional view of the residue discharge coil.

Figure 2 is a longitudinal section through a 45 rotary furnace with six retorts built into it.

In the following description a zinc distilling process is referred to by way of example.

In both examples of apparatus shown, 1 is the 50 rotary furnace and 2 the zinc retort or retorts, arranged on the axis of rotation of the furnace or approximately parallel thereto. At 3 there is shown diagrammatically a worm feed device for charging the retorts operated either by hand or by a belt drive. The charge to be reduced and the reducing medium are fed into a bunker 4 and pass from this through a slot in the worm housing 55 to the worm 3. The bunker 4 is stationary, whilst

the housing of the worm rotates together with the furnace: between the bunker and the housing there is a packing medium. 5 shows the condenser serving for the precipitation of the zinc vapours. At 6 the vapours pass into the condenser, 60 whilst the exhaust gases of condensation pass out at 7, that is to say, in the direction of the axis of rotation, a phrase which, where it appears in the claims of this specification is to be regarded as meaning either actually along the axis or parallel thereto. As, in order to prevent the formation of metal dust within the condenser, the temperature of the gases in the condenser may not be allowed to drop below the melting point of the zinc, the exhaust gases of the condenser naturally also contain a certain quantity of metal vapour which can be recovered in the form of an oxide by subsequent combustion. To this end, in Figure 2, a hood 8 is shown which serves to collect the condenser exhaust gases. In the constructional form according to Figure 1 the exhaust gases from the condenser are burnt in the space 9 and are guided back to the chamber of the rotary furnace surrounding the retort. In Figure 1 a 4% inclination of the rotary furnace 70 plant is provided for, whilst Figure 2 represents a furnace placed horizontally. In many cases it may be preferable to alter this inclination of the furnace in the manner known according to the class of raw material being treated as, for example, by compelling all materials that can only be reduced with difficulty to pass through the reduction zone very slowly, the muffles being fully charged. Under certain circumstances a horizontal position of the furnace will be insufficient 75 for this purpose and the furnace must be so inclined that the material in the retort will travel upwards. The heating of the rotary furnace is effected, in the construction shown in Figure 1, by means of a burner 10 and in Figure 2 by a burner 95 11 which projects right through the hollow shaft 3' of the feed worm 3. For the escape of the gases of combustion exhaust-gas outlets 12 are provided in the corresponding furnace heads.

In the apparatus according to Figure 1 the retort charge is introduced into the muffle by the worm 3 or the like and passes through the muffle in the direction indicated by the arrow x. The residues of the muffle process leave the muffle at 13 and pass into a coil 14 around the muffle, from the opposite end of which coil they are discharged, the end of the coil being for this purpose bent outwardly as indicated at 15. If necessary there are inserted in the coil valves to prevent the muffle gases from escaping. Each of such valves 110

may, for example, be as illustrated in Figure 1b and a valve is inserted at two points; for instance, as depicted in Figure 1c, the coil 14 may be cut at the points 38 and 39, at each of which a length of piping is removed to allow of the insertion of a complete valve as illustrated in Figure 1b, suitable flanges, as shown in Figure 1c, being for this purpose fitted to the coil 14. Each valve comprises a closure member 40 adapted to be moved into or out of contact with a cooperating seating 41 by means of a handle 42, the stem 43 connecting the closure member 40 with the handle passing through a gas-tight gland 44. As indicated, the valve seating 41 is mounted in a fitting 45 adapted, as above mentioned, to replace a portion of the coil 14 which has been removed, and provided with a branch 46 in which the gland 44 is located. In use the valves are alternately opened and closed; thus if the valve situated at the point 38 be open and that at the point 39 closed, the residue from the muffle will, on rotation of the latter, pass through the coil as far as the point 39. The valve at this point may then be opened while the former valve is closed. Thus the material is enabled to pass on its way and be discharged from the opening 15 of the coil and passage of gas is prevented on account of the fact that the valve at the point 38 is closed. Thus, the material having been discharged, the valve at the point 39 is closed and the valve located at 38 opened, and the whole cycle of operations is then repeated. Entrance of the residue into the condenser 5 is prevented by means of a retention ring 47 (Figure 1a). This construction possesses the advantage that the residue is cooled off very quickly because, with the aid of the outlets 13, it is very rapidly conveyed to the outside. Owing to the quick discharge of the residue the zinc vapours have no opportunity of becoming condensed upon it. This type of construction has the further advantage that the reactions taking place in the retort may be directly observed through the apertures 7 and 6 and it is thus possible to clear away any deposits that may have formed in the retort by introducing a suitable iron rod through the apertures. In the diagrammatic representation in Figure 1 heating of the retort is carried out upon the counter-current principle, that is movement of the combustion gases is contrary to the direction taken by the material in the retort. By locating the heating means in proximity to the charging point operation on the parallel-flow principle may be achieved.

In the constructional form according to Figure 2 the charge passes from the bunker 4 through the worm 3 to an ante-chamber 20 which is in communication with six retorts 2, so that the charge introduced enters into that one of the retorts which is at the bottom for the time being. In order to prevent any pronounced falling back of the charge from the retorts when in the uppermost position retention plates 21 are provided. At the outlet end all the retorts open into a common chamber 22 in which the condenser 5 is so mounted that the charge passes to the discharge outlet 24 through an annular space 23 between

the condenser and the walls of the chamber 22, whilst the zinc vapours enter the condenser 5 through the opening 6. The condenser is rigidly connected to the chamber 22 and to the furnace 1 and rotates together with the furnace. The residue is conducted, in a manner similar to that described with reference to Figure 1, from an outlet 24 into an annular chamber 25. The cooled residue leaves the annular chamber 25 through an outlet 26. The heating of the furnace is effected by a burner 11 which projects through the hollow shaft of the worm 3. The gases of combustion play around the whole of the six retorts 2 and pass at 27 into an annular chamber 27' which is left between the wall of the chamber 22 and the inner wall of the furnace; from this annular chamber 27' they are led into the furnace head 31 and through the pipe 12 to the outside. The residue and metal vapours both moving in the same direction as the axis of rotation of the furnace, are removed from the reduction zone separately since withdrawal of the reducing gases takes place in the centrally situated condenser 5 and the residue is removed in the annular space 23 surrounding the condenser.

What I claim and desire to secure by Letters Patent of the United States is:—

1. A process for the distillation of readily volatilizable metals such as zinc, cadmium and the like in a rotary furnace having at least one retort built into it, according to which discharge of the distillation residue is effected through at least one lateral connection from the said retort extending through the wall of the said furnace.

2. A process for the distillation of readily volatilizable metals such as zinc, cadmium and the like in a rotary furnace having at least one retort built into it, according to which discharge of the distillation residue is effected through at least one lateral connection from the said retort extending through the wall of the said furnace and thence through a chamber surrounding said furnace.

3. A process for the distillation of readily volatilizable metals such as zinc, cadmium and the like in a rotary furnace having at least one retort built into it, according to which discharge of the distillation residue is effected through at least one lateral connection from the said retort extending through the wall of the said furnace and thence through a helix surrounding said furnace.

4. A process of distilling volatilizable metals, comprising the steps of charging a rotary retort with the material to be treated, subjecting the material to heat in said retort to vaporize the metal content, feeding the material longitudinally of the retort while rotating the same, maintaining the temperature of the retort and of the material therein above the condensation point of the metal to prevent precipitation of the metal in said retort, discharging the vaporized metal from the retort in the direction of the axis of rotation thereof, and discharging the solid residue of the process radially with respect to said axis and through a wall of the furnace.

FRIEDRICH JOHANNSEN.
